UNITED STATES PATENT OFFICE.

JOSEPH A. MULCAHY, OF DEER LODGE, MONTANA.

DESIGN FOR A SPOON.

48,982.

Specification for Design.

Patented May 2, 1916.

Application filed January 3, 1916. Serial No. 70,043. Term of patent 7 years.

To all whom it may concern:

Be it known that I, JOSEPH A. MULCAHY, a citizen of the United States, and a resident of Deer Lodge, in the county of Powell and State of Montana, United States of America, have invented a new, original, and ornamental Design for a Spoon, of which the following is a specification, reference being had to the accompanying drawing, forming part thereof, in which the figure is a face view of a spoon embodying my new design.

I claim:

The ornamental design for a spoon, as shown.

JOSEPH A. MULCAHY.

Witnesses:

MABEL E. DAVIS,

LEE WILLIAMS.
